UNITED STATES PATENT OFFICE

2,461,549

SELF-LUMINOUS ASH TRAY

Helen Hull Jacobs, United States Navy

Application July 14, 1945, Serial No. 605,157

3 Claims. (Cl. 250—71)

(Granted under the act of March 3, 1883, as
amended April 30, 1928; 370 O. G. 757)

1

This invention refers to self-luminous ash-trays for use under conditions of darkness when regular illumination would be detrimental or undesired such as in sleeping rooms, on porches, and the like, or for use aboard ship or at shore stations in ward rooms or where ever desired during periods when blackout conditions prevail and when direct illumination is objectionable or undesirable but where it would be desirable to readily locate or identify an ash tray in the dark.

One object of this invention is to provide an improved ash-tray having a self-luminous portion whose glowing surface is shielded from direct view.

Further objects and advantages of this invention as well as method of construction and arrangement will be apparent from the following description and claims in connection with the accompanying drawing, the single figure of which is an isometric view, partly in section, of an ash tray embodying the invention.

The ash-tray 10 is of any suitable shape or design and formed from any suitable material and is provided with upright walls 20. The upper border of the walls 20 comprises the overhanging ledge 11, which, in the embodiment shown, is rolled or bent inwardly within the bounds of the walls 20, and reentrant downwardly as illustrated. The overhanging ledge 11 provides a recess 12 on the underside thereof, wherein is affixed in any suitable manner a coating of any suitable self-luminous or phosphorescent material capable of emitting a desired glow during darkness.

The overhanging ledge 11, and the self-luminous material being disposed on the under surface thereof in the recess 12, serves to orient the glow as indicated by the arrows, to prevent the direct glow of the phosphorescent material in the recess 12 from being seen directly, but permits its reflection from the inside surfaces of the tray to be readily discernable at short distances.

It is to be understood that various modifications

2

and changes may be made in this invention without departing from the spirit and scope thereof as set forth in the appended claims.

The invention described herein may be manufactured and used by or for the Government of the United States of America for governmental purposes without the payment of any royalties thereon or therefor.

What is claimed is:

10. 1. An ash tray comprising a container and an overhanging ledge, a self-luminous material applied to the under surface of the ledge and positioned shielded thereby.
2. An ash tray comprising a container, upright walls bounding the container, and an overhanging ledge comprising the upper border of the walls, self-luminous material applied to the under surface of the ledge and positioned shielded thereby.
15. 3. An ash tray comprising a container, upright walls bounding the container, and an overhanging ledge directed inwardly and reentrant downwardly, and comprising the upper border of the walls, self-luminous material applied to the under surface of the ledge and positioned shielded thereby.
20. 25. 3. An ash tray comprising a container, upright walls bounding the container, and an overhanging ledge directed inwardly and reentrant downwardly, and comprising the upper border of the walls, self-luminous material applied to the under surface of the ledge and positioned shielded thereby.

HELEN HULL JACOBS.
